UNITED STATES PATENT OFFICE

GEORGE W. LA SALLE, OF CANTON, OHIO, ASSIGNOR TO HERCULES MOTORS CORPORATION, OF CANTON, OHIO, A CORPORATION OF OHIO

PUMP AND IGNITION DRIVE UNIT

Application filed May 21, 1931. Serial No. 538,999.

My invention relates to pump and ignition drive units more particularly adapted for use in water cooled internal combustion engines.

In the usual commercial forms of internal combustion engines, the pump for the cooling system of the engine, and the magneto, or the distributor, for the ignition system, are driven through a timing gear train from the engine crank shaft.

10 In order to avoid duplication of auxiliary shafts, a single auxiliary shaft driven by the timing gear train is usually used to drive both the pump and either a magneto, or a distributor, or both in the case of dual ignition.

15 In the mass production of engines of different power outputs for use as power units in various types of industrial or commercial vehicles, equipment, and machinery, such as 20 motor trucks, busses, well drilling rigs, and the like, it has been found that the greatest demand is for that horse power which may be produced by a 4 cylinder engine. Consequently a manufacturing plant which is 25 equipped to produce 4 cylinder engines at low cost, may attain the greatest possible economy in the production of higher powered 6 cylinder engines, with the greatest use of the same sized parts in both the 4 and 6 30 cylinder engines, whereby the manufacturing economies attained by the use of the jigs, fixtures, and other equipment for mass production of the 4 cylinder engines may be used to a large extent in the production of 35 lesser numbers of 6 cylinder engines.

20 In the usual 4 cylinder engine, when magneto ignition is used, the speed of the magneto armature shaft equals the speed of the engine crank shaft, and accordingly the pump shaft speed is usually equal to the engine 40 crank shaft speed.

25 On the other hand, in a 6 cylinder engine, standard practice requires that the magneto armature shaft speed be one and one-half 45 times the engine crank shaft speed. In both 4 and 6 cylinder engines the speed of the distributor shaft in a battery and coil ignition system is equal to one-half the engine speed.

50 The capacity of a pump for a 6 cylinder

engine must be greater than that for a 4 cylinder engine, and it has been found that the same size pump may be used for both a 4 cylinder engine and a 6 cylinder engine, if the pump is driven at the engine speed in the 55 4 cylinder engine, and at one and one-half times the engine speed in the 6 cylinder engine.

From another standpoint, the more compact are the overall dimensions of any internal combustion engine, the more generally it may be used as a power unit for the many different kinds of commercial and industrial vehicles, equipment, and machinery.

Very frequently, a particular engine is disqualified for use in a particular location, because of an excessive dimension in a single direction of only a small fraction of an inch.

In general, the objects of the present improvements include the provision of a novel 70 pump and ignition drive unit, whereby a very compact 6 cylinder engine may be attained, and whereby substantial economies may be effected in the production of 6 cylinder engines in connection with the production 75 of greater numbers of 4 cylinder engines, or vice versa.

The foregoing and other objects are attained by the apparatus, parts, improvements and combinations, which comprise the present invention, and which are particularly and distinctly pointed out and set forth in the appended claims forming part hereof.

In general terms the improvements hereof may be described as including a frame, which 85 may be the frame or crank case and cylinder block of an internal combustion engine, a main drive shaft such as the crank shaft of an internal combustion engine, the main drive shaft being operatively mounted on the 90 frame, and an auxiliary and preferably unitary drive apparatus, the auxiliary drive apparatus being adapted in the case of an internal combustion engine for driving auxiliary mechanisms which may be either a magneto, 95 or a distributor, or both, together with a water pump for the cooling system of the engine, and the auxiliary drive apparatus including longitudinally extending mounting means secured to and supported by the frame, 100

a pair of longitudinally extending auxiliary shafts journalled in the mounting means, means operatively connecting one of the auxiliary shafts with the main drive shaft, and 5 the other auxiliary shaft being adapted for driving connection with the auxiliary mechanisms, one end of each auxiliary shaft being located adjacent the opposite end of the other, and preferably, internal gear means oper- 10 atively connecting the adjacent auxiliary shaft ends, and the frame and mounting means preferably including walls forming communicating compartments for lubricant about the means operatively connecting the 15 drive shaft and the auxiliary shaft and about the means operatively connecting the auxiliary shafts.

A preferred embodiment of the improvements is illustrated in the accompanying 20 drawings forming part hereof, in which

Figure 1 is a perspective view of an internal combustion engine including the present improvements;

Fig. 2, a fragmentary side elevation thereof, with portions of the engine and auxiliary drive apparatus illustrated in section;

Fig. 3, a transverse fragmentary sectional view of the auxiliary drive apparatus as on line 3—3, Fig. 2; and

Fig. 4, a transverse fragmentary sectional view thereof as on line 4—4, Fig. 3, the auxiliary drive apparatus being illustrated in Fig. 4 in driving connection with a distributor.

Similar numerals refer to similar parts throughout the drawings.

The internal combustion engine indicated generally at 10 includes in combination with other usual parts of an engine, a frame 11 which may include a cylinder head 12, a cylinder block and crank case 13, and an oil pan 14.

A crank shaft 15 is operatively mounted on the frame 11 within the crank case in a 45 usual manner, and for the purposes of the present invention, the crank shaft 15 may be considered broadly as a main drive shaft.

The improved preferably unitary auxiliary drive apparatus is indicated generally by 16, 50 and includes longitudinally extending mounting means indicated generally by 17 which are secured to and supported by the frame 11.

The mounting means 17 may include a journal member 17a, and a journal and housing member 17b. The members 17a and 17b extend longitudinally and are preferably separably connected with each other at abutting and opposite ends as by means of bolts 18, and the journal member 17a preferably re- 60 movably fits in a longitudinally extending bore 19 formed at one end of the cylinder block and crank case 13.

A pair of longitudinally extending auxiliary shafts 20a and 20b are journalled in 65 the mounting means, the shaft 20a being

preferably journalled in a bearing 21a in the journal member 17a, and the shaft 20b being preferably journalled in a bearing 21b in the journal and housing member 17b.

Means are provided which may include a timing gear train indicated generally by 22 for operatively connecting the auxiliary shaft 20a with the main drive or crank shaft 15. The timing gear train 22 may include a gear 23 secured at the outer end of the auxiliary shaft 20a, and the gear 23 is gear connected with the shaft 15 by means of any usual gearing, and the rotary speed ratio between the crank shaft 15 and the auxiliary shaft 20a is preferably 1:1, the engine 10 being a 6 cylinder engine, but the timing gear train 22 being the same as may be used for a 4 cylinder engine.

The frame 11 preferably includes a gear cover 13a for the gear train 22, and the gear cover 13b, the crank case 13, and the journal and housing member 17b of the mounting means 17 include walls forming communicating compartments, whereby lubricant from the crank case passes into and out of the interior of the housing member 17b during operation of the engine, lubricating the bearings and gears of the auxiliary drive apparatus 16.

Preferably internal gear means indicated generally by 24 are provided for operatively connecting the adjacent opposite ends of the auxiliary shafts 20a and 20b.

The internal gear means 24 preferably include an internal gear 25, which may be formed directly upon the inner end of the auxiliary shaft 20a, and the gear 25 meshes with a pinion 26 which may be formed directly upon the inner end of the auxiliary shaft 20b. The internal gear 25 and the pinion 26 are located preferably between the bearings 21a and 21b.

For carrying out the more specific purposes of the improvements, that is to say for enabling the use of the aforesaid 1:1 timing gear train on a 6 cylinder engine, and at the same time driving the auxiliary mechanisms at the necessary or desired speeds, the ratio between the rotary speed of the auxiliary shaft 20a and the rotary speed of the auxiliary shaft 20b is 1:1½. The auxiliary shaft 20b may extend any desired distance beyond the bearing 21b, and is adapted for operative and driving connection with one or more auxiliary mechanisms.

As illustrated the outer end of the shaft 20b is directly connected as by coupling means 27 with the armature shaft 28 of a magneto 30 for providing magneto ignition for the 6 cylinder engine 10. The necessary speed of rotation of the armature shaft 28 is 1½ times the speed of rotation of the crank shaft 15, and such necessary speed of rotation of the armature shaft is attained

by the use of the improved drive apparatus 16.

The journal and housing member 17b extends beyond the bearing 21b, and terminates at an end wall 31 which is separably connected with a pump case member 32, as by means of cap screws 33, and the end wall 31 and the pump case member 32 form the case for a water pump which is indicated generally by 34, and which is located between the magneto coupling 27 and the bearing 21b.

The shaft 20b extends through suitable apertures formed in the end wall 31 and the case member 32, and the central portion 20b' of the shaft 20b comprises the shaft for the pump 34.

Any usual stuffing boxes 35a and 35b may be interposed, respectively, between the central shaft portion 20b' and the end wall 31, and between the central shaft portion 20b' and the case member 32.

An impeller 36 is secured on the central shaft portion 20b' within the impeller chamber 37 which is formed in the case member 32; and the case member 32 has formed therein, in addition to the chamber 37, a suitable inlet duct 38 and a suitable outlet duct 39 which communicate respectively with the radiator and the cooling chambers of the cylinder block of the engine 10 in a usual manner.

Between the bearing 21b and the pump 34 the shaft 20b may be adapted for operative connection with a distributor, as by means of a spiral gear 40 which may be formed directly on the shaft 20b.

In Fig. 4, the spiral gear 40 is illustrated in operative connection with a spiral drive pinion 41 secured on the lower end of the shaft 42 of a distributor 43, and in order to attain the necessary rotary speed for the distributor shaft 42 of $\frac{1}{2}$ the rotary speed of the crank shaft 15 of the engine, the ratio between the rotary speed of the auxiliary shaft 20b and the distributor shaft 42 is 3:1.

The pump 34 for the 6 cylinder engine 10 may be the same size pump as may be used for a 4 cylinder engine, because of the fact, that by the use of the foregoing improved drive apparatus 16, the speed of rotation of the pump impeller 36 is $1\frac{1}{2}$ times the speed of rotation of the crank shaft 15, whereas in a 4 cylinder engine adequate capacity is attained by driving the pump at engine speed by the use of the preferred internal gear means 24 for operatively connecting the auxiliary shafts 20a and 20b, and by locating the gear means 24 between the timing gears and the pump, quiet operation of the drive apparatus 16 is attained; lubrication for the drive apparatus 16 may be provided from the engine crank case as aforesaid; and, of even greater importance, the desired maximum compactness for the drive apparatus

and the engine as a whole is attained, by reason of the fact that with internal gears it is necessary to displace the axes of the auxiliary shafts 20a and 20b only a relatively short distance from each other.

I claim:

1. A unitary apparatus for use as an auxiliary drive for an internal combustion engine and the like, the apparatus including longitudinally extending mounting means adapted to be secured to and supported by a wall of an internal combustion engine, a pair of longitudinally extending shafts journaled in the mounting means, one of the shafts being adapted for operative connection with the engine, and the other shaft being adapted for operative connection with one or more auxiliaries for the engine, one end of each shaft being located adjacent the opposite end of the other, and gear means operatively connecting the adjacent shaft ends.

2. A unitary apparatus for use as an auxiliary drive for an internal combustion engine and the like, the apparatus including longitudinally extending mounting means adapted to be secured to and supported by a wall of an internal combustion engine, a pair of longitudinally extending shafts journaled in the mounting means, one of the shafts being adapted for operative connection with the engine, and the other shaft being adapted for operative connection with one or more auxiliaries for the engine, one end of each shaft being located adjacent the opposite end of the other, and internal gear means operatively connecting the adjacent shaft ends.

3. A unitary apparatus for use as an auxiliary drive for an internal combustion engine and the like, the apparatus including longitudinally extending mounting means adapted to be secured to and supported by a wall of an internal combustion engine, a pair of longitudinally extending shafts journaled in the mounting means, one of the shafts being adapted for operative connection with the engine, and the other shaft being adapted for operative connection with one or more auxiliaries for the engine, one end of each shaft being located adjacent the opposite end of the other, and gear means operatively connecting the adjacent shaft ends so that the rotary speed of the shaft operatively connected with the auxiliaries is one and one-half times the rotary speed of the shaft adapted for operative connection with the engine.

4. A unitary apparatus for use as an auxiliary drive for an internal combustion engine and the like, the apparatus including longitudinally extending mounting means adapted to be secured to and supported by a wall of an internal combustion engine, a pair of longitudinally extending shafts journaled in the mounting means, one of the shafts being adapted for operative connection with

the engine, and the other shaft being adapted for operative connection with one or more auxiliaries for the engine, one end of each shaft being located adjacent the opposite end of the other, and internal gear means operatively connecting the adjacent shaft ends so that the rotary speed of the shaft operatively connected with the auxiliaries is one and one-half times the rotary speed of the shaft adapted for operative connection with the engine.

5. A unitary apparatus for use as an auxiliary drive for an internal combustion engine and the like, the apparatus including longitudinally extending mounting means adapted to be secured to and supported by a wall of an internal combustion engine, a pair of longitudinally extending shafts journaled in the mounting means, one of the shafts being adapted for operative connection with the engine, and the other shaft being adapted for operative connection with one or more auxiliaries for the engine, one end of each shaft being located adjacent the opposite end of the other, and gear means operatively connecting the adjacent shaft ends, and the mounting means including walls forming a casing for the gear means.

6. A unitary apparatus for use as an auxiliary drive for an internal combustion engine and the like, the apparatus including longitudinally extending mounting means adapted to be secured to and supported by a wall of an internal combustion engine, a pair of longitudinally extending shafts journaled in the mounting means, one of the shafts being adapted for operative connection with the engine, and the other shaft being adapted for operative connection with one or more auxiliaries for the engine, one end of each shaft being located adjacent the opposite end of the other, and internal gear means operatively connecting the adjacent shaft ends, and the mounting means including walls forming a casing for the gear means.

45 7. A unitary apparatus for use as an auxiliary drive for an internal combustion engine and the like, the apparatus including longitudinally extending mounting means adapted to be secured to and supported by a wall of an internal combustion engine, a pair of longitudinally extending shafts journaled in the mounting means, one of the shafts being adapted for operative connection with the engine, a plurality of drive connections on the other shaft, each drive connection being adapted for driving an auxiliary for the engine, one end of each shaft being located adjacent the opposite end of the other, and gear means operatively connecting the adjacent shaft ends.

8. A unitary apparatus for use as an auxiliary drive for an internal combustion engine and the like, the apparatus including longitudinally extending mounting means

adapted to be secured to and supported by a wall of an internal combustion engine, a pair of longitudinally extending shafts journaled in the mounting means, one of the shafts being adapted for operative connection with the engine, a plurality of drive connections on the other shaft, each drive connection being adapted for driving an auxiliary for the engine, one end of each shaft being located adjacent the opposite end of the other, and internal gear means operatively connecting the adjacent shaft ends.

9. A unitary apparatus for use as an auxiliary drive for an internal combustion engine and the like, the apparatus including longitudinally extending mounting means adapted to be secured to and supported by a wall of an internal combustion engine, a pair of longitudinally extending shafts journaled in the mounting means, one of the shafts being adapted for operative connection with the engine, a plurality of drive connections on the other shaft, each drive connection being adapted for driving an auxiliary for the engine, one end of each shaft being located adjacent the opposite end of the other, and gear means operatively connecting the adjacent shaft ends so that the rotary speed of the shaft operatively connected with the auxiliaries is one and one-half times the rotary speed of the shaft adapted for operative connection with the engine.

10. A unitary apparatus for use as an auxiliary drive for an internal combustion engine and the like, the apparatus including longitudinally extending mounting means adapted to be secured to and supported by a wall of an internal combustion engine, a pair of longitudinally extending shafts journaled in the mounting means, one of the shafts being adapted for operative connection with the engine, a plurality of drive connections on the other shaft, each drive connection being adapted for driving an auxiliary for the engine, one end of each shaft being located adjacent the opposite end of the other, and internal gear means operatively connecting the adjacent shaft ends so that the rotary speed of the shaft operatively connected with the auxiliaries is one and one-half times the rotary speed of the shaft adapted for operative connection with the engine.

11. A unitary apparatus for use as an auxiliary drive for an internal combustion engine and the like, the apparatus including longitudinally extending mounting means adapted to be secured to and supported by a wall of an internal combustion engine, a pair of longitudinally extending shafts journaled in the mounting means, one of the shafts being adapted for operative connection with the engine, a plurality of drive connections on the other shaft, each drive connection being adapted for driving an auxiliary for the en-

gine, one end of each shaft being located adjacent the opposite end of the other, and gear means operatively connecting the adjacent shaft ends, and the mounting means including walls forming a casing for the gear means.

12. A unitary apparatus for use as an auxiliary drive for an internal combustion engine and the like, the apparatus including 10 longitudinally extending mounting means adapted to be secured to and supported by a wall of an internal combustion engine, a pair of longitudinally extending shafts journaled in the mounting means, one of the shafts 15 being adapted for operative connection with the engine, a plurality of drive connections on the other shaft, each drive connection being adapted for driving an auxiliary for the engine, one end of each shaft being located 20 adjacent the opposite end of the other, and internal gear means operatively connecting the adjacent shaft ends, and the mounting means including walls forming a casing for the gear means.

25 In testimony that I claim the above, I have hereunto subscribed my name.

GEORGE W. LA SALLE.
